UNITED STATES PATENT OFFICE.

DAVID HENDERSON, OF WATERBURY, CONNECTICUT.

WIRE-DRAWING APPLIANCE.

SPECIFICATION forming part of Letters Patent No. 768,602, dated August 30, 1904.

Application filed October 30, 1903. Serial No. 179,246. (No model.)

To all whom it may concern:

Be it known that I, DAVID HENDERSON, of Waterbury, county of New Haven, State of Connecticut, have invented certain new and useful Improvements in Wire-Drawing Machines; and I do hereby declare the following to be a full, clear, and exact description of the invention, such as will enable others skilled in the art to which it pertains to make and use the same.

My invention is for the purpose of drawing wire by means of a drum at once without any preliminary drawing, and I accomplish this by means of a device which overcomes the need of reducing the end of the wire (by swaging) beforehand for any greater length than is sufficient to extend through the die and only protrude far enough beyond to allow the jaws of a gripping-vise to take hold. The common practice is to reduce the end of the wire in this manner and in addition thereto to draw, by means of a separate device for the purpose, a certain length more before the drum is put into operation, the amount thus reduced and drawn beforehand being sufficient to reach from the vise, which is located on or near the top of the drum, diagonally downward to the die, which is at about the level of the flange and rests in a holder permanently fastened to a bench or table. At first the wire as it is drawn winds diagonally from the die around the drum to the vise. After this the direction of the pull and the friction due to the pressure against the drum immediately bring it down and it passes from the die onto the fillet of the flange, which acts as an abutment, constantly crowding it upward, or, in terms of the trade, causing it to "cast." The drum is turned slightly tapering, and the gripping-vise is located high up to permit the wire to cast with as little resistance as possible. The height of the drawing-surface is but a small part of the total height of the drum, and above this the diameter is reduced, the wire when it comes up to the reduced part lying on loosely and the friction of the coils in contact with the drawing-surface doing most of the work of drawing and reducing the strain on the vise. In my invention the drum may be as above described; but the die instead of being sta-

tionary is held in a die-holding carriage made to move freely and easily along a curved inclined guide or track located adjacent to it. At the beginning of the first revolution the die is at the point on this guide or track which is nearest to the vise. As the revolution continues, while drawing the wire through the die the drum also pulls the die and its carriage along the guide, the inclination and curvature being such as will bring them down to about the level of the flange at once. Having thus located the die, the wire passes onto the drum and casts in same manner as above described.

Referring to the accompanying drawings, Figures I, II, and III show plan, front, and side views, respectively, of my invention. Fig. IV is a side view, on an enlarged scale, of the die-holding carriage and die.

In Figs. I, II, and III the position of the vise B at the time the die-holder has reached the lower extremity of its travel is indicated by broken lines, and the direction of the pull of the wire at this time is indicated by the broken line N. The position which is assumed by the die and its carriage shortly afterward and which is maintained till all the wire is drawn is indicated by the broken lines at A in Figs. I and III. The direction of the pull is now indicated by broken line L in Figs. I and II, which passes directly from the die onto the fillet of the flange G.

The method of operating is as follows: The reduced end of the wire is passed through the die D and gripped by the vise B. The drum E is then revolved in the direction indicated by the arrow, and in drawing the wire it pulls the die D along the guide F, to which it is joined by the holder C, into the final position A.

In Fig. IV, R is a roller which fits the track and takes the pressure on the die from the holder through the pin P, on which it revolves.

It is to be noted that the movement of the die begins with the beginning of the revolution of the drum, and the final position which it assumes is reached almost instantly, the movement from a position close to the vise to a position in the plane of the flange taking place in a fractional part of the first revolution. Bringing the die down thus quickly, the wire as it at first winds around the drum as

sumes a steep angle, which subsequently assists very materially the casting of the wire. In designing the guide or track this consideration determines the inclination and curvature.

5 The cylindrical guide or track F of the drawings shows a simple and practical device for directing the movement of the die; but I do not confine myself to this mechanism, since there are guides of various other forms that 10 may be applied for the same purpose within the principle of my invention.

I claim—

1. In a wire-drawing machine the combination with a rotatable flanged wire-drum having a vise for gripping the end of the wire located at or toward the end of said drum opposite the flange, of a traveling die through which said wire is drawn, a guide or track adjacent to said drum, inclined and curved from 15 a point relatively close to said vise to a point approximately in the same plane as said flange for guiding said die in its movement, and means for connecting said die to said guide or 20

track, whereby said die on putting said drum into operation is immediately drawn by the 25 pull exerted on the wire into a position which causes said wire to pass onto said drum and cast upward, substantially as described and shown.

2. In a wire-drawing machine the combination with a rotatable wire-drum of a traveling die through which said wire is drawn, a guide or track adjacent to said drum, and means for connecting said die to said track, whereby the 30 pull exerted on the wire by rotating said drum causes said die to travel as described, thus enabling the drawing process to take place without the use of a separate drawing-in device, substantially as described.

In testimony whereof I have signed my name 35 to this specification in the presence of two subscribing witnesses.

DAVID HENDERSON.
